DESIGN FOR A PLASTIC UNIT FOR HAND-BAGS OR THE LIKE

Joseph L. Friedman, New York, N. Y.

Application October 19, 1945, Serial No. 123,035

Term of patent 7 years

(Cl. D87—3)

To all whom it may concern:

Be it known that I, Joseph L. Friedman, a citizen of the United States of America, residing in New York city, county of New York and State of New York, have invented a new, original, and ornamental Design for a Plastic Unit for Handbags or the like, of which the following is a specification, reference being had to the accompanying drawing, forming part thereof, wherein, unit for handbags or the like showing my new design.

I claim:

The ornamental design for a plastic unit for handbags or the like, substantially as shown.

JOSEPH L. FRIEDMAN.
